UNITED STATES PATENT OFFICE.

LEWIS G. O'DONNELL, OF COSCOB, CONNECTICUT.

AIR-PRESSURE LUBRICATOR.

1,167,593.

Specification of Letters Patent.

Patented Jan. 11, 1916.

Application filed May 4, 1915. Serial No. 25,819.

To all whom it may concern:

Be it known that I, LEWIS G. O'DONNELL, a citizen of the United States, residing at Coscob, in the county of Fairfield and State of Connecticut, have invented certain new and useful Improvements in Air-Pressure Lubricators, of which the following is a specification.

This invention relates to air pressure lubricators, that is to say, it belongs in the class with devices intended to serve oil to contrivances of any description, tube-cleaners used to remove the scale from steam-boiler tubes, cutting and riveting tools of all kinds, wherein the working fluid employed is compressed air.

For the purpose of explaining this invention, an ordinary tube cleaner is shown. It is necessarily connected with the air service pipe by a flexible hose pipe, because it must be freely moved about and turned into various positions. The hose pipe for carrying the air to the cleaner is customarily of rubber material. Oil having an injurious action upon rubber, the air-carrying tube cannot at the same time afford a passage for oil. It is not desired that there should be more than one pipe connected with the cleaner or tool. If the oil were served in an oil-carrying tube separate from the rubber air-carrying pipe or hose, the arrangement would be very inconvenient even if the two pipes were attached to each other.

It is the purpose, therefore, of this invention to produce a compressed air lubricator having parts of special construction and arrangement, and in which the air-carrying pipe is as usual of rubber, and the oil-carrying tube is of metal extending within the rubber pipe.

In the accompanying drawings, throughout which the same letter is used to refer to the same part, Figure 1 represents a vertical section through the T-connection and various pipes and tubes, and shows the oil-feeding device in position and all parts assembled. Fig. 2 is a vertical section of the nozzle on the end of the metal oil-carrying tube. Fig. 3 is a top view of an annular member having passes through it by way of which the air enters the air-carrying pipe. The lower surface of the member affords a seat for the air check valve that controls the passages in the said member.

Fig. 4 is a side view of the manner in which this invention is connected up for use, and

shows an air-serving pipe by which the compressed air reaches this invention, and an air-carrying pipe by which the air travels to the cleaner or tool, and which contains the oil-carrying tube. Fig. 5 is a pipe-coupling attached to the end of the air-carrying pipe. Fig. 6 is a top plan view of the pipe-coupling shown in Fig. 5.

In all the figures excepting the fourth, the scale of drawing is full size.

Considering the drawings, there will be noted in Fig. 4 an air filter A. This filter is advantageously employed in practice in connection with air-operated tools to catch any foreign bodies that might otherwise find their way into the cleaner or tool. Connected with the filter is an air-serving pipe a, which is connected with a T-connection B. The connection B is in its turn connected by an air-carrying pipe b with a pipe-coupling or the like C, which is connected up with a tube-cleaner D having the cutters d.

As best illustrated in Fig. 1, an oil-feeding device E is arranged vertically above the T-connection B, and is in communication therewith. A small tube e connects the oil-feeding device with the air-serving pipe a, in order that the air pressure may be the same in that device as elsewhere. The oil-feeding device may advantageously have the sight feed F, in the throat by which it is placed in communication with the T-connection. Within the connection B an oil tube f extends for a distance downwardly, and is arranged to drop oil into a funnel G beneath it. The tube g of the funnel extends downwardly, and is joined by the union H to a metal oil-carrying tube h, extending within the rubber air-carrying pipe b as illustrated.

The pipe b, which, as stated, is of rubber, has clamped to it a metal mouth-piece or terminal J, and a union j connects the terminal J with the T-connection B, clamping between them an annular member K, which is provided with air passages k extending through it in the direction of its axis and between its center and rim. The lower surface of the member K affords a valve seat for a check valve L, yieldingly seated by means of the spring M acting between the valve and a collar m on the fixed stem or tube g of the funnel G.

Now considering Fig. 5, there will be seen a screw N that passes inwardly through the

wall of the pipe-coupling C, and engages a curved hook plate n, by which the nozzle O that terminates the oil-carrying tube is removably secured within the pipe-coupling.

5 In Fig. 2 is illustrated that the nozzle O is provided with a check valve P opening outwardly, and yieldingly seated by means of the spring Q.

In furtherance of the explanation of the mode of operation of this invention, let it be assumed that the parts have been assembled and connected up as set out in Fig. 4, and Fig. 1. The T-connection B and the oil cup E are arranged vertically. Air from pipe a will unseat valve L and pass into the tube cleaner D. At the same time air enters the oil cup E by way of the small tube e, equalizing the pressures and enabling the oil to feed drop by drop in the usual manner. The oil falls into the funnel G and is carried along by the air through the tube h, and driven out of the nozzle O into the mechanism of the tube cleaner D. It is desirable if practicable that no oil shall 25 reach the interior of the pipe B. To avoid that condition, the nozzle O is provided with the spring-seated check valve P. If it were not for the valve P, the oil would drip from the nozzle when the cleaner D 30 happened to be lowered, some oil always remaining in the tube h, even after the feed of the oil has been shut off. The valve P keeps the remaining oil in the tube h for future use.

35 In connection with the explanation of the mode of operation of this invention, it should be stated that the check valve L, described as located at the entrance to the air-carrying hose or pipe b, is intended to and 40 does partially obstruct the flow of air at the outset into that hose. Air pressure must overcome the spring M before the air can flow into the hose b. Meantime, air is flowing freely through the unobstructed oil-carrying tube h, taking the oil with it into the cleaner D, and insuring full lubrication 45 thereof whenever air is served to the cleaner D and practically independent of the amount of air consumed by the cleaner for 50 its operation, within limits varying considerably.

It will be understood that the spring Q shown in Fig. 2, which holds the ball valve P to its seat, is not intended to resist the 55 passage of the air at all, and it is, therefore, made only strong enough to fully seat the ball valve when no air is passing.

Having now described this invention and explained the mode of its operation, what I 60 claim is:-

1. In an air pressure lubricator, the combination with an air-service pipe, of a T-connection secured to the said pipe, an oil-feeding device arranged vertically above the 65 said connection in communication therewith,

an air tube connecting the said device and the air-service pipe, a funnel located in the said connection and arranged to receive the oil from the oil-feeding device, a rubber air-carrying pipe connected with the said T-connection and having a pipe-coupling at its other end, a metal oil-carrying tube connected with the said funnel and extending within the rubber air-carrying pipe and having a nozzle at its end arranged in the said pipe-coupling, and means for removably securing the said nozzle within the said pipe-coupling.

2. In an air-pressure lubricator, the combination with an air-service pipe, of a T-connection, an oil-feeding device arranged vertically above the said connection in communication therewith, an air tube connecting the said device and the said air-service pipe, a funnel located in the said connection and arranged to receive the oil from the oil-feeding device, a rubber air-carrying pipe connected with the said T-connection and having a pipe coupling at its other end, a spring-seated check valve in the said connection opening downwardly and controlling the passage of air into the said air-carrying pipe, a metal oil-carrying tube extending within the rubber air-carrying pipe and having a nozzle at its end arranged within the said pipe-coupling, a spring-seated check valve in the said nozzle opening outwardly, and means for removably securing the nozzle within the said pipe-coupling.

3. In an air pressure lubricator, the combination with an air-service pipe, of a T-connection, an oil-feeding device arranged vertically above the said connection in communication therewith, means for connecting the said device with the said air-service pipe, the said device being constructed to deliver oil into the said connection, a rubber air-carrying pipe connected with the said T-connection and having a pipe-coupling at its other end, a metal oil-carrying tube extending within the said air-carrying pipe and having a nozzle at its end arranged within the said pipe-coupling, means for securing the said nozzle removably within the said pipe-coupling, and means arranged within the said T-connection for directing the oil from the said oil-feeding device into the said metal oil-carrying tube.

4. In an air pressure lubricator, the combination with an air service pipe, of a T-connection, an oil-feeding device arranged vertically above the said connection in communication therewith, means for connecting the said device with the said air-service pipe, a rubber air-carrying pipe connected with the said T-connection and having a pipe-coupling at its other end, a spring-seated check valve within the said connection opening downwardly and controlling the passage of air into the said air-carrying pipe, a

metal oil-carrying tube extending within the rubber air-carrying pipe and having a nozzle at its end arranged within the said pipe-coupling, means for securing the said 5 nozzle removably within the said pipe-coupling, a spring-seated check valve within the said nozzle opening outwardly, and means arranged within the said T-connection for directing the oil from the oil-feeding device 10 into the said metal oil-carrying tube.

5. In an air pressure lubricator, the combination with an air-service pipe, of a T-connection, an oil-feeding device in communication with the said connection, means for 15 connecting the said device with the said air-service pipe, the said device being constructed to deliver oil into the said connection, a

rubber air-carrying pipe connected with the said T-connection and having a pipe-coupling at its other end, a metal oil-carrying 20 tube extending within the said air-carrying pipe and having a nozzle at its end arranged within the said pipe-coupling, means for securing the said nozzle removably within the said pipe-coupling, and means arranged 25 within the said T-connection for directing the oil from the said oil-feeding device into the said metal oil-carrying tube.

In testimony whereof I affix my signature in presence of two witnesses.

LEWIS GRANT O'DONNELL.
